COLLAPSIBLE BEDDING SUPPORTING DEVICE

Richard E. Schmidt, Salt Lake City, Utah, and
James B. Green, Pocatello, Idaho

Application October 12, 1953, Serial No. 385,384

2 Claims. (Cl. 5—319)

This invention relates to new and useful improvements and structural refinements in devices for supporting bedding such as bed covers, sheets, and the like, so that such bedding does not come in direct contact with the feet of the occupant of the bed, and the principal object of the invention is to provide a device of the character herein described, which may be quickly and easily folded or collapsed to an inoperative position when the use thereof is not desired.

An important feature of the invention, therefore, resides in the provision of a frame which may be applied to the customary mattress of the bed so as to support the bedding in an elevated position, but which may be swung to a collapsed out-of-the-way position on the mattress so that it is unobtrusive and need not be altogether removed from the bed when not in use.

Another feature of the invention resides in the construction of the entire device from a single piece of rod, such as a wire rod, or the like, while some of the advantages of the invention lie in its efficient operation and in its adaptability to economical manufacture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a fragmentary perspective view of the invention in use;

Figure 2 is a vertical sectional detail, taken substantially in the plane of the line 2—2 in Figure 1; and

Figure 3 is a fragmentary sectional view, taken substantially in the plane of the line 3—3 in Figure 2.

Referring now to the accompanying drawings in detail, the collapsible supporting device is designated generally by the reference character 10 and consists of a frame 12 which is preferably formed from a single piece of wire rod, or the like, and includes a horizontal linearly straight lower portion 14 which functions in the nature of a combined frame anchoring and fulcruming member, as will be hereinafter described.

A pair of upstanding connecting vertical pieces 16 are provided at the ends of the portion 14 and are laterally disposed and equipped at their respective upper ends with a pair of inwardly projecting, horizontal shoulder members 18 which, in turn, are connected together by an arched upper member 20, the latter generally U-shaped in form.

When the invention is placed in use, it is handily positioned and bridled over one end portion of a conventional mattress 22 so that the lower member 14 of the frame 12 is interposed between the spring and mattress and underlies the mattress in a transverse relation, while the side pieces 16 straddle the lengthwise sides of the mattress and the shoulder members 18 rest rockably on the upper

2

surface of the mattress, as is clearly shown in the accompanying drawing. In this position the portions 14, 16 and 18 are harnessed on the mattress and the arched member 20 extends upwardly from the mattress and supports the bed clothing 24 in an elevated position above the feet of the occupant.

However, when the use of the invention is not desired, the entire frame 12 is simply rotated in the direction of the arrow 26 in Figure 3 with the lower portion 14 anchored under the mattress acting as a fulcrum, so that the upper oblique angled portion 20 of the frame rests firmly on the top of the mattress in a collapsed position, as indicated by the dotted lines 28.

In this position, the entire frame is quite unobtrusive and need not be removed from the mattress when the use thereof is not desired.

It will be also observed that the shoulder members 18, engageable with the upper surface of the mattress 22, will function as effective stops or abutments for sustaining the frame either in its operative or inoperative position, as the case may be.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

What is claimed as new is as follows:

1. A bed mattress attachment which functions to elevate bed clothing at the foot end of the mattress, which stays in position on the mattress and is foldable downwardly to an out-of-the-way position when its use is not desired comprising an endless one-piece frame embodying a linearly straight anchoring and fulcruming member which takes a position interposed between the bottom of the mattress and top of the usual bed spring and extends transversely across the mattress in contact with the underside of the mattress, a pair of vertical laterally disposed end members at right angles to and connected to the respective ends of said anchoring member and bridging the respective lengthwise sides of the mattress and having lateral turned-in bends at their upper ends, said bents paralleling said fulcruming member and resting atop and in contact with the mattress and constituting retaining and shoulder forming members, and a generally U-shaped arch-forming upper member of a length less than the length of said fulcruming member and having a bight portion horizontally disposed and also parallel to said fulcruming member and end portions joined to the turned-in bends.

2. The structure defined in claim 1 and wherein said fulcruming member, laterally disposed end members, and turned-in bends are all in the same plane and said arch-forming U-shaped member is at an approximate obtuse angle in respect to the plane of said fulcruming member, end members and bends, whereby when it is swung in the direction of the top of the mattress, it assumes direct out-of-the-way contact with the mattress.
